[57] **CLAIM**

The ornamental design for a high torque, low rpm motor/generator, as shown and described.

DESCRIPTION

FIG. 1 is a perspective view of the high torque, low rpm motor/generator embodying the design of the present invention;

FIG. 2 is a typical elevational view thereof, all elevational views being identical to the view shown in FIG. 2;

FIG. 3 is a top plan view thereof; and,

FIG. 4 is a bottom view thereof.

FIG. 1

FIG. 2

FIG. 3

FIG. 4
